L. WÖERNER

FLUID PRESSURE DEVICE

Filed Oct. 19, 1922

INVENTOR
LEO WOERNER

BY *G. G. Duffman*
ATTORNEY

UNITED STATES PATENT OFFICE.

LEO WOERNER, OF ST. LOUIS, MISSOURI.

FLUID-PRESSURE DEVICE.

Application filed October 19, 1922. Serial No. 595,702.

My invention relates to a fluid pressure device for the purpose of controlling the pressure supply and at the same time operating an audible or visual signal to warn the attendant of abnormal pressure in the system. The object of my invention is to improve the construction of the pressure controlled device itself and also to provide improved supporting means and operating connections therefor.

In the accompanying drawings in which one form of my device is illustrated, Fig. 1 is a side elevation, the upper part of the support being shown in section and a fragment 15 only of the alarm device being shown; Fig. 2 is a horizontal section, and Fig. 3 is an enlarged detail view showing the adjustable connection between one of the contact arms and its operating lever.

20 1 indicates a tubular support carried by a base 2. Secured to the support 1 at a point intermediate of its length is a bracket 3 carrying a table 4 upon which is secured the pressure controlled device and the alarm. 25 The support 1 is divided into compartments by a pair of partition walls 5, spaced apart by a filler block 6. Arranged in the central compartment is a stop member 7 described in a 30 separate application. Attached to the lower end of the stop member 7 is a cable 16 which passes downwardly, around a sheave 17, and thence to any suitable valve control mechanism. A cable 26 is attached to the upper end of the stop member 7 and extends upwardly 35 over a sheave 27 and thence downwardly to a weight 28 in one of the lateral compartments of the support. The purpose of this weight 28 is to return the stop member 7 to normal position.

40 30 is a central member carried by the table 4 and having secured to it a pair of diaphragms 31. Secured centrally in each of the diaphragms is a rod 32 sliding in a spider 33. The spiders 33 are secured to lugs on the member 30. Coil springs 34 surround the rods 32 between the diaphragms 31 and the spiders 33. On the end of each of the rods 32 is a yoke 35 pivoted to an operating lever 36 and an equalizing lever 37. 38 are cross pieces secured to brackets 39 on the member 30 and having pivoted to them the central parts of the lever 30 and the ends of the levers 37. It will be understood that the pivot openings, either in the yoke 35 or

levers 36 and 37 must be slightly elongated 55 to permit the necessary movements. This elongation, however, is so small that no attempt has been made to show it in the drawings. Pivoted to the brackets 39 are levers 40 connected by links 41 with the levers 36. 60 42 are contact arms pivoted to the levers 40 at 43. One of the arms 42 is adapted to actuate the arm 13 by contact with its down-turned end 15 and the other to actuate the alarm device. In order that the arms 42 65 may be adjusted, the inner end of each is provided with a slot 45 concentric with the pivot 43, through which slot passes a clamping screw 44. Pressure is admitted between the diaphragms through a pipe 49. A pressure gauge 50 is preferably used to assist in adjusting the device.

The operation of the device is as follows. Pressure is admitted between the diaphragm 31 through the pipe 49 and forces the said 75 diaphragm apart against the pressure of the springs 34. This movement is communicated through the rods 32, levers 36 and links 41 to the lever 40 causing their respective contact arms 42 to actuate the arm 13 and lever 47 80 when abnormally high pressure is reached.

Having fully described my invention what I claim as new and desire to secure by Letters Patent of the United States is:

1. In a device of the class described, the 85 combination with a support, of a diaphragm secured thereto, a rod carried by said diaphragm, a spider carried by said support and forming a guide for said rod, a spring surrounding said rod between said diaphragm and spider, a yoke on said rod, a lever pivoted to one end of said yoke, an equalizing bar pivoted to the other end of said yoke, a control arm, and a link operatively connecting said lever to said control 95 arm.

2. In a device of the class described, the combination with an annular member, of a diaphragm forming a side wall of said member and carrying a rod, a spider supported 100 from said member and forming a bearing for said rod, a coil spring surrounding said rod between said diaphragm and spider, a pair of oppositely disposed supports, and a lever system pivotally carried by said support and 105 actuated from said rod.

3. In a device of the class described, the combination with an annular member, of a

diaphragm forming a side wall of said member and carrying a rod, a spider supported from said member and forming a bearing for said rod, a coil spring surrounding said rod between said diaphragm and spider, a pair of oppositely disposed supports, an operating lever pivoted to one of said supports, an

equalizing arm pivoted to the other of said supports, a yoke carried by said rod and connecting said lever and arm, and an actuating arm carried by said operating arm. 10

In testimony whereof, I have hereunto set my hand.

LEO WOERNER.
